UNITED STATES PATENT OFFICE.

PAUL M. RAINY, OF GLEN RIDGE, NEW JERSEY, ASSIGNOR TO WESTERN ELECTRIC COMPANY, INCORPORATED, OF NEW YORK, N. Y., A CORPORATION OF NEW YORK.

PRINTING MECHANISM.

1,362,639.

Specification of Letters Patent. Patented Dec. 21, 1920.

Application filed November 3, 1917. Serial No. 200,088.

To all whom it may concern:

Be it known that I, PAUL M. RAINY, a citizen of the United States, residing at Glen Ridge, in the county of Essex and State of New Jersey, have invented certain new and useful Improvements in Printing Mechanism, of which the following is a full, clear, concise, and exact description.

This invention relates to printing mechanism, and more particularly to improvements in printing telegraph receiving apparatus and the like.

The principal object of this invention is to provide efficient and reliable means whereby a printing mechanism may be automatically arrested, when desired, to begin the first word of each new paragraph a predetermined or desired distance from the margin or edge of the printing medium.

The invention disclosed in the accompanying drawings is embodied in a telegraph receiving printer comprising stationary selecting mechanism, a stationary paper platen and printing elements adapted to be moved transversely of the printer. It is obvious, however, that the invention is applicable to any typewriting mechanism wherein either the paper platen or printing mechanism is arranged for transverse movement.

For the accomplishment of the above object means are provided whereby the type carriage, for example, when returned for commencing a new line, may be arrested a suitable distance from the edge of the printing medium in order that the first word of a new paragraph may be set-in or indented without necessitating the usual loss of time and wearing of parts in spacing the type carriage step by step a suitable distance from the margin to begin a paragraph.

More specifically the invention comprises means whereby a normally idle member carried by the type carriage may be actuated and caused to engage a suitable stop on the frame of the printer to arrest the type carriage a suitable distance from what is normally its initial position. Means are also provided for restoring the co-operating parts of the carriage actuating or spacing mechanism the instant the type carriage is arrested.

The above and other features of this invention will be fully set forth in the following description and claims and will be more readily understood by reference to the ac-

companying drawings in which Figure 1 is a perspective view of a portion of a telegraph receiving printer embodying the invention; Fig. 2 is a vertical sectional view taken just to the right of the center of the selecting mechanism and just to the right of the special code bars shown at the left of Fig. 1, and Fig. 3 is an enlarged view of the carriage arresting mechanism shown in Fig. 1.

The invention herein disclosed embodied in a printing telegraph receiving apparatus deals primarily with the relative transverse movements between the platen and printing mechanism and only so much of the apparatus as is essential to a clear understanding of the invention will be described. For a clear understanding of the printing, selecting and power driving mechanism necessary for the construction of a complete operative machine, reference may be made to a co-pending application of Harry Pfannenstiehl, Serial No. 173,546, filed June 8, 1917, wherein all the essential details are shown and described in full.

The printing mechanism herein disclosed is of standard typewriter construction. The type carriage 20, including the necessary printing elements and actuating levers, is supported by a suitable frame 21 and rotatable shaft 22, which shaft may be journaled in the frame 21 or supported in any desired manner. The carriage 20 is adapted to be moved transversely of the printer from left to right step by step, or one step for each character or group of signaling impulses, and is adapted to be released and moved to the left in one operation for beginning a new line, as will presently appear. On the frame 21 is mounted a dash-pot carriage check or stop comprising a piston or air chamber 72, and a piston rod or plunger 73. The purpose of the carriage stop is to provide means for arresting the carriage quickly without shock or rebound and at any desired distance from the side of the frame 21 to allow the necessary margin on the printing medium. The head 74 of the plunger 73 normally engages the frame of the carriage 20 at 23 when the carriage is returned for beginning a new line, but under certain conditions, as will appear later, the plunger head 74 may be caused to engage the member 63 which is pivotally supported by the carriage 20.

100
105
110

A paper platen is indicated at 81 with a sheet of paper or printing medium 82 passing thereover, on which the desired characters may be recorded.

- 5 A rotary power-driven shaft 25 is pro-
vided which carries a battery of cams and
coöperates with suitable bell crank levers
or operative members to cause the printing
of the desired character or operation to be
10 performed. The cam shaft may be jour-
naled in the frame of the printer or mount-
ed in any suitable manner and is preferably
controlled by line current impulses, as
15 clearly explained in the above-mentioned co-
pending application. Secured to the rota-
table shaft 22, by a key or any suitable
means, is a worm-gear 71 which coöperates
with a rack 70 for stepping the type car-
riage transversely of the platen. A locking
20 disk member 66 is also carried by the shaft
22. The member 66 is normally held abut-
ting against the end of the rack 70 by means
of a spring 75, and carries two pins or ex-
tensions 67 (only one of which is clearly
25 shown), which are normally held so that
they do not engage the member 68 or any
portion of the type carriage when it is re-
turned to its initial position, but the disk
may be rotated so that the pins 67 are moved
30 into the path of travel of the member 68
for certain purposes as will presently ap-
pear. The shaft 22 carries a ratchet 76
which is actuated by a cam 80, carried by
the shaft 25, coöperating with a reciprocat-
35 ing member 79, on the free end of which is
a member 78 carrying a pawl 77. The pawl
77, as will be clearly seen from Fig. 1, is
moved forward by the cam 80 to engage a
tooth of the ratchet 76 and in returning to
40 normal under the action of spring 83 ro-
tates the ratchet 76 and consequently the
shaft 22.

The selecting mechanism consists preferably of five selecting magnets 30, 31, 32, 33 and 34 (only three of which are shown in Fig. 2), five selecting latches 35, 36, 37, 38 and 39, and a corresponding number of selecting bars 40, 41, 42, 43 and 44, all of which are controlled by the said selecting magnets. In addition to the five selecting magnets there may be provided a starting magnet for releasing the cam shaft to start the mechanism in operation. The selecting mechanism is operated preferably by various combinations of five positive and negative selecting impulses with an additional impulse following each group of selecting impulses for releasing the cam shaft. The impulses may preferably arrive over a single line from a distant station and may be distributed to the selecting and starting magnets by means of a Baudot distributor or any other well-known distributing system.

In addition to the printing of the characters there are various functions to be per-

formed such, for example, as line spacing, shift and unshift, carriage return, carriage return and paragraph indenting, etc. These various functions are performed mechanically, by rotating cams coöperating with 70 bell crank levers and suitable operative members.

Carriage return and paragraph indenting.

Let us assume that a message is being 75
printed, and that after reaching the end of
a line or sentence it is desired to return the
type carriage and begin a new paragraph.
These operations, in a telegraph receiving
printer, would normally be accomplished by 80
sending a group of impulses to effect the re-
turn of the type carriage, which group of
impulses would be followed by a sufficient
number of groups of impulses to space the
carriage forward the desired distance for 85
the commencement of a new paragraph.
Approximately ten separate groups of im-
pulses would ordinarily be required to space
the carriage sufficiently for paragraph in-
denting. By means of applicant's invention 90
the return of the type carriage and the
proper positioning of the carriage for the
commencement of a new paragraph may be
effected by the transmission of a single
group of impulses. For the purpose of re- 95
turning the type carriage and arresting it
prematurely or a predetermined distance
from its initial starting position, a special
code bar is provided which may be selec-
tively actuated by line current impulses. 100
When the selecting bars 40 to 44 are se-
lectively actuated to permit the code bar
50 to move forward under the action of a
spring 51 it performs three distinct func- 105
tions. First, the bent-over portion 52 of
the bar 50 engages a pull-bar 53 and moves
it forward into the path of a reciprocating
member 54 carried by a bell crank lever 55.
The lever 55 is pivotally mounted on a sup- 110
porting rod 56 and is adapted to be actuated
or rocked by a cam 57 during each
revolution of the cam shaft 25; secondly,
the upwardly extending arm 58 of the code
bar 50 engages a member 59 which is pivot- 115
ally supported on a rod 60 and moves
member 61 into the path of a pin 62 car-
ried by the pivotally supported member 63,
and, thirdly, the forward movement of the
member 59 rocks an arm 64 and by means 120
of the member 65 connected thereto rotates
the disk 66, thereby moving the pins 67 into
the path of travel of the member 68. Now,
immediately after the five selecting impulses
have been received and a selection set up, a 125
sixth or starting impulse releases the cam
shaft, and the cam 57, carried thereby, act-
ing upon the bell crank lever 55, draws the
pull bar 53 downward and disengages the
rack 70 from the worm-gear 71. The instant 130
the rack 70 is actuated sufficiently to disen-

gage the worm-gear 71, the disk member 66, under the action of the spring 75, engages the offset portion 76 and holds the rack in depressed position until the type carriage is 5 returned by the action of a suitable spring and tape 69. During the return movement of the type carriage the pin 62, rigidly secured to the member 63, rides up on the flange portion of the member 61, thereby 10 raising the member 63 so that it engages the head 74 of the plunger 73, and arrests the type carriage a predetermined distance from the side of the printer, and by means of the member 68 engaging the pins 67 the 15 locking disk member 66 is forced back against the action of spring 75, thereby releasing the rack 70 and permitting it to return into engagement with the worm-gear 71. It is essential that the means provided 20 for arresting the type carriage and the means provided for permitting the return of the rack 70 be so regulated or adjusted that the rack 70 will be caused to reengage the worm-gear 71 the instant the type carriage 25 is arrested, so that no time will be lost in commencing to record the characters of the new line.

Carriage return without paragraph indenting.

30 When it is desired to return the type carriage for the commencement of a new line, other than when starting a new paragraph, a group of impulses may be transmitted 35 which will cause the selection of the special code bar 84. The code bar 84 in moving forward engages the pull-bar 53 and moves it into the path of the reciprocating member 54 as hereinbefore described in connection with 40 the special code bar 50. The member 59 is normally held in the position shown in Fig. 1, that is, in its idle position or in such position that the member 61 does not engage the member 62 and also in such position that the 45 pins 67, carried by the disk member 66, are moved out of the path of travel of the member 68 or any portion of the type carriage. Therefore, since the special code bar 84 is not provided with means to actuate the member 59, the only act performed by the forward movement of the code bar 84 is to place the pull-bar 53 in position to be actuated by the reciprocating member 54. When the 50 sixth or starting impulse is received and the cam shaft releases, the cam 57 locks the bell crank lever 55 and in acting upon the pull-bar 53 withdraws the rack 70 from engagement with the worm-gear 71, thereby permitting the type carriage to be returned to the 55 extreme left-hand position by means of a 60 spring and tape 69. Since the member 63 has not been actuated the type carriage proper will strike against the head 74 of the plunger 73 and the member 68 will engage the disk portion 66 instead of the pins 67, thereby permitting the carriage to return to the extreme left-hand side of the printer. 65

Applicant's invention while shown embodied in a telegraph receiving printer is not to be considered as limited to such a 70 structure, as it is equally applicable to printing mechanism employing a stationary printing basket and a paper platen movable transversely of the printing basket, as is well known in the typewriter art. 75

What is claimed is:

1. In a telegraph receiving printer, the combination of a movable carriage, a frame for said carriage, carriage stop mechanism mounted on said frame, and means supported by said carriage and controlled by line current impulses for prematurely arresting the said carriage for beginning a new paragraph. 80

2. In a telegraph receiving printer, a 85 movable type carriage, means for moving said carriage in one direction step by step, means for returning the said carriage in one operation, and a member supported by said carriage and controlled by line current impulses for automatically arresting the said carriage before it reaches its initial position for commencing a new paragraph. 90

3. In a telegraph receiving printer, the combination of a movable carriage, an operative member carried by said carriage, means controlled by line current impulses for advancing the said carriage in one direction step by step, means controlled by line currents for releasing said carriage, means 95 for returning the said carriage when released, and means controlled by line current impulses for operating said member to arrest the carriage during its return movement a predetermined distance from its 100 initial position. 105

4. A printing telegraph receiver comprising a movable carriage, a frame for said carriage, a dash-pot mounted on said frame, a normally idle member mounted on said carriage, and selectively operable means controlled by line current impulses to effect engagement of said normally idle member and said dash-pot whereby the carriage may be arrested a predetermined distance from its 110 initial position. 115

In witness whereof, I hereunto subscribe my name this 31st day of October A. D., 1917.

PAUL M. RAINES.
